C. A. HIRTH,

DEVICE FOR ACCELERATING THE FEED OF BALL BEARING BALLS TO GRINDING MACHINES.

APPLICATION FILED OCT. 19, 1911.

UNITED STATES PATENT OFFICE.

CARL ALBERT HIRTH, OF CANNSTATT, NEAR STUTTGART, GERMANY.

DEVICE FOR ACCELERATING THE FEED OF BALL-BEARING BALLS TO GRINDING-MACHINES.

1,061,241.

Specification of Letters Patent.

Patented May 6, 1913.

Application filed October 19, 1911. Serial No. 655,625.

To all whom it may concern:

Be it known that I, CARL ALBERT HIRTH, a citizen of the Empire of Germany, and a resident of the city of Cannstatt, near Stuttgart, in the Kingdom of Wurtemberg and Empire of Germany, have invented certain new and useful Improvements in Devices for Accelerating the Feed of Ball-Bearing Balls to Grinding-Machines, of which the following is a specification.

This invention relates to a device for accelerating the velocity of ball-bearing balls during their feed to the grinding machines, and has for its object to provide means whereby the balls are given a certain velocity substantially the same as that of the grinding surfaces or grinding disks. Thereby the balls are carried along by the grinding disks without being stopped, and on the other hand, the velocity of the grinding surfaces is not impaired by the feed of the balls, which is desirable to be kept at a certain high speed.

For this purpose my invention consists in the arrangement for conducting the balls to be fed between two surfaces sufficiently loose so that the balls receive by the relative movement of one surface to the other the desired feed velocity.

The invention consists more particularly of a ball-feeding hopper, a rotary member, a stationary member, and means between the stationary and rotary member for conducting the balls, said means being arranged in screw-line fashion and increasing in pitch from the feed hopper, and a guide-channel adapted to receive the balls from the said conducting means and guide the balls received from the conducting means to the axis of the rotary member, whereby the balls are greatly accelerated in their movement.

In the accompanying drawings, Figure 1 is a vertical axial section, Fig. 2 is a horizontal section taken on line *a*—*b* of Fig. 1, showing the several feed tubes, and Fig. 3 shows a modified form of feed hopper in which the balls are conducted in one single cylindrical feed instead of a plurality of individual feed tubes.

Similar letters of reference indicate corresponding parts.

Referring to the drawings, the feed-hopper *c* is provided with a number of balls for ball-bearings intended to be fed to the grind-

ing machine which pass by gravity from the hopper *c* to the plurality of tubes *d*. In the form shown in Fig. 3 the plurality of tubes *d* is replaced by a single cylindrical feed. At the lower end of the feed tubes *d* or feed-cylinder *m*, a rotary member *e* is arranged that has its shaft *e*¹ movable in bearings *e*² and its shaft *e*³ movable in bearings *e*⁴, ball-bearings *e*⁵ being provided, as is well known, for causing the least possible loss of energy by friction. The rotary member *e* is further provided at its lower end with a cut-out portion for the guiding of a belt which belt serves to rotate the member *e*. The member *e* is surrounded by a stationary sleeve *n* which is spaced from the outer surface of the member *e* about the distance of the radius of the balls to be handled by the device. The member *n* is supported by the standard *n*¹ which also supports the bearings *e*⁴ before referred to. The rotary member *e* in the embodiment shown in Fig. 1 is provided with a groove in width substantially equal to the diameter of the balls to be handled by the device which groove terminates at the upper surface of the rotary member *e* and is capable of being brought in registration with the lower ends of the tubes *d* or the cylinder *m*, and terminates at its lower end in the guide-channel *h* which passes from the circumference of the rotary member *e* toward the axis of the same at the lowermost part of the rotary member *e*. The guide-channel *h* communicates with a guide-channel *k*¹ of a member *k*. This serves to feed the balls to a guide-tube *l*¹ of an injector *l*, which injector is set in operation by a compressed fluid passing through the tube *o* and into the feed-pipe *w*, carrying with it by means of the injector *l*¹ action the balls in the guide-tube *l*¹ and forcing the same at a high velocity through the feed-tube *w*.

The rotary member *e* is provided with a groove at its outer surface which is arranged screw-line fashion and which has its smallest pitch uppermost of the rotary member *e*, with its pitch increasing in axial direction away from the upper end of the rotary member *e*. In the embodiment shown in the drawing, the stationary sleeve *n* is provided with grooves *g* in alignment with the feed-tubes *d* or parallel with the feed cylinder axis. The depth of the grooves *f* and *g* is about equal to the diameter of the balls, and

when the upper end of the groove *f* is in registration with the upper end of a groove *g*, a ball in the feed tube *d* or feed cylinder *m*, held immediately above it, will drop into the upper-ends of the grooves *f* and *g*.

5 By the rotation of the rotary member *e* the mouth of the groove *f* is brought opposite the groove *g*, and the ball immediately above the two registering grooves, which heretofore was seated on the edge of the member *e*, may drop into the groove *g* and the groove *f*. By the rotation of the rotary member or cylinder *e* the ball is conducted from the upper end of the groove *g* of the 10 sleeve *n* to the lowermost end of the same, and is prevented by the walls of the tube *g* from rotating with the rotary member *e*. As the pitch of the screw increases, the velocity of the ball in the groove *g* increases and thereby the balls are given a certain accelerated velocity. The balls thus guided by the coöperating grooves *g* and *f* are finally brought in registration with the guide-channel *h* which is inclined in position relatively 15 to the axis. By the transfer of the balls from the groove *g* to the channel *h*, the balls which were moved heretofore in a straight line in the groove *g* receive a circular movement with an additional acceleration. In order to prevent shocks, the channel *h* at 20 its beginning must be provided with a backwardly directed chute or inclination. From the channel *h* the balls pass through the stationary channel *h*¹. The action of the described device, with the exception of that heretofore described for the injector, is such that the balls are guided by means of the channel *h*¹ without further mechanism to the grinding machine. In the event, however, 25 that the velocity of the balls should be an especially large one, the injector device is applied to the channel *h*¹ and thereby the balls are given an additional velocity. The fluid which is used may be either gas, air, 30 oil, etc. This fluid then forms a cushion between the several balls which acts to prevent impact of the balls with each other and prevents an impairment of their trueness.

For using the invention it is not absolutely necessary that both of the surfaces *e* and *n* which are relatively movable toward each other, should be provided with grooves since under certain circumstances it is sufficient that one or the other may have a 35 smooth surface without grooves, acting however, in such a manner as to prevent the balls from moving out of the groove.

My invention therefore consists in having two members relatively movable to each other by means of which the velocity of the balls when fed to grinding machines is accelerated, the balls being given first a linear movement and then a circular movement, and in the means for bringing about the 45 desired coöperation.

I have described an embodiment of my invention, but changes may be made therein without departing from the spirit and scope of the invention.

Having thus described my invention, I claim as new and desire to secure by Letters Patent:

1. A device for accelerating the feed of ball-bearing balls to grinding machines, comprising members relatively movable to each other and spaced ball-guiding distance apart, one of said members having a ball-guiding groove of increasing inclination toward its outlet. 75

2. A device for accelerating the feed of ball-bearing balls to grinding-machines, comprising members relatively movable to each other and spaced ball-guiding distance apart, ball-guiding grooves in said members arranged angularly to each other, and a communicating ball-guiding groove in one of said members, inclined to the axis thereof. 85

3. A device for accelerating the feed of ball-bearing balls to grinding machines, comprising a stationary member provided with grooves in the direction of movement of the balls, and a rotary member spaced ball-guiding distance from said stationary member and provided with a screw-line groove transverse to the first-named grooves and increasing in pitch from one end of the rotary member to the other. 90

4. A device for accelerating the feed of ball-bearing balls to grinding machines, comprising a hollow cylindrical member having interior grooves parallel with the axis of the member, and a cylindrical rotary member within the hollow cylindrical member having grooves arranged screw-line fashion on the exterior surface thereof and increasing in pitch from one end of the rotary member to the other, the said groove being adapted to be brought in registration with the grooves of the stationary member and conduct the balls held between the grooves with a constantly increasing speed. 105

5. A device for accelerating the feed of ball-bearing balls to grinding machines, comprising a movable member having an inlet for the balls, and a ball-guide having an outlet for the balls, said movable member and ball-guide coöperating to increase the speed of the balls from said inlet to said outlet. 115

6. A device for accelerating the feed of ball-bearing balls to grinding machines, comprising a stationary member, a rotary member, means for guiding a ball therebetween, said means being arranged to give the ball a constantly increasing velocity, and a guide-channel in said rotary member adapted to receive the ball from said means, said channel being inclined to the axis of rotation of said member. 125

7. A device for accelerating the feed of 130

ball-bearing balls to grinding machines, comprising a feed chute adapted to hold a plurality of balls, means for receiving the balls from the chute and giving them a constantly increasing velocity under linear movement, means for receiving the balls from said means and imparting to the ball a rotary movement, and means for receiving the ball from said last-named means for guiding the ball in linear movement at its end velocity.

8. A device for accelerating the feed of ball-bearing balls to grinding machines, comprising a feed chute adapted to hold a plurality of balls, means for receiving the balls from the chute and giving them a constantly increasing velocity under linear movement, means for receiving the balls from said means and imparting to the ball a rotary movement, and means for receiving the ball and additionally accelerating the same or imparting to it the end velocity.

9. A device for accelerating the feed of ball-bearing balls to grinding machines, com-

prising members relatively movable to each other and spaced ball-guiding distance apart, 25 one of said members having a ball-guiding groove of increasing rate of progression toward its outlet, and means for feeding balls equidistantly to said ball-guiding groove.

10. In a device for accelerating the feed of ball-bearing balls to grinding machines, members movable relatively to each other, adapted to receive a ball, and a member having a channel adapted to receive the ball 35 from said members and having an inclined portion to avoid any impact of the ball while it enters the channel.

In testimony, that I claim the foregoing as my invention, I have signed my name in 40 presence of two subscribing witnesses.

CHARL ALBERT HIRTH.
